BRAKE BEAM WITH GUIDE LUG

Walter H. Baselt, Flossmoor, Ill., assignor to
American Steel Foundries, Chicago, Ill., a cor-
poration of New Jersey

Application July 6, 1946, Serial No. 681,637

15 Claims. (Cl. 188—222.6)

1

This invention relates to railway brake equipment and more particularly to a novel truss type brake beam.

A general object of the invention is to design a novel brake beam wherein the truss structure and brake head are formed as a single casting.

Another object of the invention is to provide an integrally cast guide lug on the outboard surface of each brake head for the purpose of supporting the beam from an associated support structure such as a guide bracket on an associated railway car truck.

Another object of the invention is to design a beam such as above described wherein the component parts are so formed and arranged as to afford maximum strength and minimum weight.

Another object of the invention is to provide a recess or pocket in each of the brake beam guide lugs inboardly of the extremity thereof for the purpose of reducing the mass of metal to promote solidity of the casting at a critical point whereat the beam is supported in torque engagement with the car truck. These pockets are also adapted to receive foreign matter which may collect within the support brackets for the beam, thus reducing the tendency for such matter to cause a jamming of the guide lugs in said brackets.

The foregoing and other objects and advantages of the invention will become apparent from a consideration of the following specification and the accompanying drawings wherein:

Figure 1 is a fragmentary top plan view of a preferred embodiment of the invention, portions of the beam being broken away;

Figure 2 is a front view of the structure shown in Figure 1;

Figure 3 is an end view of the structure shown in Figures 1 and 2, and Figures 4 and 5 are fragmentary sectional views taken respectively in the planes indicated by the line 4—4 of Figure 3 and 5—5 of Figure 1;

Figure 6 is a fragmentary top plan view of a modification of the invention;

Figure 7 is a front view of the structure shown in Figure 6;

Figure 8 is an end view of the structure shown in Figures 6 and 7;

Figures 9 and 10 are fragmentary sectional views taken respectively in the planes indicated by the lines 9—9 of Figure 8 and 10—10 of Figure 6;

Figure 11 is a fragmentary top plan view of another embodiment of the invention;

Figure 12 is a front view of the structure shown in Figure 11; and

2

Figure 13 is an end view of the structure shown in Figures 11 and 12.

Describing the invention in detail and referring first to the embodiment illustrated in Figures 5—5 inclusive, the novel brake beam comprises a T-section compression member 2 including a longitudinal vertical web 4 forming the head of said T and a longitudinal horizontal web 6 forming the leg of the T. The web 6 merges with a tension member 7 in a gusset 8 forming a continuation of the web 6, and both of the webs 4 and 6, as well as the tension member 7, merge with a vertical wall or web 10 integrally formed on the rear surface of the front wall 12 of a conventional brake head 14 formed on each end of the beam.

Only one of the brake heads 14 is shown in Figure 1 inasmuch as the beam is substantially identical at opposite ends thereof. The brake head is formed with a conventional keyway 18 for the reception of associated key means (not shown) for securing an associated brake shoe (not shown) to the front face of the brake head wall 12.

The rear surface of the brake head wall 12 and the outboard surface of the web 10 are integrally formed with a guide lug 20 preferably disposed in a diagonal plane and adapted for reception within an associated support bracket (not shown). The lug 20 is provided with substantially identical top and bottom recesses 22 adapted to lighten the beam and to form convenient pockets for the accommodation of foreign matter which may collect in the associated guide bracket, thus reducing the tendency of such matter to collect in the bracket forwardly of the lug 20 thereby restricting forward movement of the beam. The recesses 22 are preferably terminated inboardly of the outboard extremity of the lug 20, so that the latter bears at its outboard end against the associated support bracket along an uninterrupted surface, thus preventing gouging of the bracket.

Referring to Figure 2, it may be noted that the lug 20 is tapered at 24 at its inboard end to afford a strong connection to the brake head. By means of this construction a relatively strong and light guide lug structure is provided resulting in a substantial economy in the manufacture of the beam. For a similar purpose the tension member 7 is tapered at 26 at its point of connection to the brake head walls 10 and 12, and the web 4 of the compression member is similarly tapered as indicated at 28 (Figure 2).

Referring now to Figure 5, it will be seen that the web 6 of the compression member 2 is in-

integrally formed with a vertical wall or web 38 intermediate the ends of the beam to afford a connection to the horizontal and vertical walls 32 and 34 of a strut 36 which is connected between the tension and compression members 2 and 7, as best seen in Figure 1. The strut 36 is provided with a brake lever slot 38 and a pin opening 40 traversing said slot and adapted for the reception of a pin (not shown) adapted to afford a fulcrum for the brake lever (not shown). The strut 36 is connected at its forward or front end to the tension member by horizontal and vertical webs or walls 42 and 44 respectively.

Thus it will be seen that I have devised a novel brake beam in which all of the component parts are integrally formed as a single casting so constructed as to afford maximum strength with minimum weight.

Referring now to the modified embodiment of the invention illustrated in Figures 6-10 inclusive, it will be understood that the beam therein shown is substantially identical with that of Figures 1-5 except that the tension member 7 is a T-section member and the pocket 22 in the bottom of the lug 20 is eliminated. Referring to Figure 6, it will be seen that the tension member 7 comprises a vertical web 9 merging with the front wall 12 of the brake head 14 and a horizontal wall or web 11 merging with the web 6 of the compression member 2. The parts of this beam corresponding to those of the beam shown in Figures 1-5 inclusive are identified by corresponding numerals.

Another embodiment of my novel brake beam is shown in Figures 11-13 wherein the beam is similar to that shown in Figures 1-5 except that the guide lug 28 is provided on its top surface with a flange 46 merging with a portion 48 of the vertical web 4 of the compression member 2 at a point outboardly of the brake head wall 10. In this embodiment of the invention the pockets or recesses 22 are terminated outboardly of the plane of the flange 46 which serves a dual function of reinforcing the juncture of the lug 28 and the associated beam parts and of affording a stop adapted for engagement with the outboard surface of the associated truck frame bracket to limit outboard movement of the beam relative to the truck frame, thereby preventing a binding action of the lug 28 within the bracket.

It is to be understood that I do not wish to be limited by the exact embodiments of the device shown which is merely by way of illustration and not limitation as various and other forms of the device will, of course, be apparent to those skilled in the art without departing from the spirit of the invention or the scope of the claims.

I claim:

1. A steel railway brake beam casting comprising a truss having a compression member, a tension member, a brake head with a forward wall adapted to carry associated brake shoe means on its forward surface and a substantially vertical rear wall merging at its forward edge with the rear surface of said forward wall, said compression member having a T-section with a vertical rear web forming the head of the T and merging with the rear edge of said rear wall, said tension member being of greater thickness than the leg of said T-section and merging with the inboard edge of said forward wall and with the leg of said T-section, and a guide lug merging with the outboard surface of said rear wall and extending forwardly therealong from a point in longitudinal alignment with the head of said T-section

5 to the outboard edge of said front wall, said lug extending outboardly of the outboard margin of said front wall and presenting top and bottom guide surfaces for cooperation with an associated truck frame bracket.

10 2. A brake beam comprising a single casting including a brake head with a front wall and a substantially vertical rear wall merging therewith and extending rearwardly therefrom and approximately perpendicularly with respect thereto, a compression member with a substantially vertical web merging with said rear wall, said member having a substantially horizontal web, a tension member merging with said horizontal web and with both of said walls, a guide lug integrally formed on the outboard face of said rear wall for reception within an associated support structure, and a pocket in at least one of the top and bottom surfaces of said lug spaced from the outboard end thereof and adapted to accommodate foreign matter collected within said structure.

15 3. A brake beam according to claim 2 wherein the lug slopes upwardly and forwardly, and the vertical web of the compression member extends 20 outboardly beyond the rear wall of the brake head, and a flange is provided on the outboard end of said vertical web, said flange merging with the top of the lug inboardly of the pocket and being spaced from and generally parallel to the rear wall of the brake head.

25 4. A steel railway brake beam comprising a truss having a compression member, a tension member, a brake head with a forward wall adapted to carry associated brake shoe means on 30 its forward surface and a substantially vertical rear wall merging at its forward edge with the rear surface of said forward wall, said compression member having a T-section with a substantially vertical rear web forming the head of said 35 T-section and merging with the rear edge of said rear wall, said tension member being of greater thickness than the leg of said T-section and being flared at the outboard end of said tension member, said outboard end of the tension member merging with the inboard edge of the front wall, with the inboard surface of the rear wall, and with the leg of said T-section at a point closely 40 adjacent the head thereof, and a guide lug merging with the outboard surface of said rear wall and extending from the rear edge thereof to the juncture with said front wall and extending outboardly from the outboard margin of said front wall to afford top and bottom guide surfaces outboardly thereof for cooperation with an associated truck frame bracket, the head of said T-section extending outboardly beyond said rear wall and being formed with a flange approximately 45 parallel to and spaced from the rear wall and merging with the lug.

50 5. A brake beam comprising a single casting 55 including tension and compression members merged at their ends to form a truss, a brake head at each end of said truss comprising a front wall merging with the tension member, said head including a rear wall extending angularly from the front wall and merging with the compression member, a guide lug formed on the outboard face of said rear wall and adapted for cooperation with an associated support structure, and pockets in the top and bottom of said lug spaced from the outboard extremity thereof and adapted to accommodate foreign matter collecting in said structure.

60 6. A steel railway brake beam casting comprising a truss having a T-section compression mem-

ber having front and rear webs defining respectively a leg and head of said T, a tension member, a brake head with a forward wall adapted to carry associated brake shoe means on the forward surface thereof, said brake head having a substantially vertical rear wall merging at its forward edge with the rear surface of said forward wall and merging at the rear edge of said rear wall with the rear web, a flat guide lug merging with the outboard surface of said rear wall and sloping upwardly and forwardly in a plane diagonal to the plane of the truss, the rear web extending outboardly beyond the outboard surface of said rear wall, and a flange spaced from said rear wall and connecting the outboard extremity of said rear web to the top surface of said lug at a point spaced inboardly from the outboard extremity thereof, and top and bottom guide surfaces on said lug spaced outboardly of said flange.

7. A unit brake beam formed as a single casting comprising a compression member having a T-section portion, a tension member merging with said portion, a brake head comprising a forward wall with a brake shoe engaging surface on the forward face thereof, a vertical wall merging with said forward wall and with at least one of said members, and a guide lug merging with the outboard face of said wall and with at least one of said members, said lug being tapered outboardly of said rear wall at the inboard extremity of said lug.

8. A unit brake beam according to claim 7 wherein the T-section portion of the compression member includes a substantially vertical web extending outboardly of the vertical brake head wall, and said web is provided with a flange spaced from and extending generally parallel to said vertical brake head wall.

9. A unit brake beam according to claim 7 wherein the tension member is of T-section and comprises a substantially vertical web forming the head of its T and connected to the inboard edge of the forward wall of the brake head.

10. A unit brake beam according to claim 7 wherein the portion of the tension member which merges with the T-section portion of the compression member is flared in width and tapered in thickness toward the brake head walls.

11. A brake beam casting comprising tension and compression members, a brake head with a

substantially vertical rear wall integrally formed therewith and a front wall integrally formed with said rear wall, and a guide lug integrally formed with the outboard surface of the rear wall and with the rear surface of the front wall and extending outboardly from said head to afford support for said beam from an associated support structure, the lug being provided with a pocket in the top surface thereof, said pocket being spaced from the outboard extremity of said lug to afford substantially continuous bearing through the breadth thereof at said extremity against said support structure.

12. A brake beam casting comprising tension and compression members, a brake head with a substantially vertical rear wall merging with said members, a guide lug merging with the outboard face of said wall, said guide lug having top and bottom surfaces, and a pocket in at least one of said surfaces spaced from the outboard end thereof.

13. A brake beam casting according to claim 12 wherein the compression member comprises a web extending outboardly of the rear brake head wall and said web is formed with a flange spaced from said wall outboardly thereof and merging with the top of the lug.

14. A brake beam casting according to claim 12 wherein the brake head comprises a front wall and the tension member is of T-section with a front substantially vertical web merging with the inboard edge of the forward brake head wall.

15. A brake beam casting according to claim 12 wherein the brake head comprises a front wall and the tension member is flared in width towards its outboard end which merges with both brake head walls and is tapered in thickness towards its merger with said walls.
